FEEDER ARRANGEMENT FOR CIRCULAR
KNITTING MACHINESRichard Schmidt, Stuttgart, Vaihingen, Germany, assignor
to Franz Morat G.m.b.H., Stuttgart-Vaihingen, Germany

Filed Sept. 6, 1960, Ser. No. 54,155

Claims priority, application Germany Sept. 7, 1959
30 Claims. (Cl. 66—131)

The present invention relates to a feeder arrangement for circular knitting machines, and more particularly to a feeder arrangement for supplying a yarn to the dial and cylinder needles of the machine during selectable knitting periods.

One object of the present invention is to provide a small yarn feeder member which is very light, and can be easily operated by remote control requiring very little power.

Another object of the present invention is to provide a feeder arrangement by which a 1 x 1 rib cuff knitted of two yarns can be knitted to an interlock fabric.

Another object of the present invention is to provide a feeder arrangement which can be operated by electromagnetic means.

Another object of the present invention is to provide feeder members of such small size that several feeder members can be provided at each feed station for supplying different yarns, which may be selected.

Another object of the present invention is to provide at each feeding station of a circular knitting machine, a movable feeder member for supplying a yarn in addition to a yarn supplied through a stationary feeder plate.

A further object of the present invention is to provide a feeder arrangement by which a yarn is supplied to the dial and knitting needles of a circular knitting machine so as to be knitted into a fabric in a selectable length, whereupon the yarn is cut off and the feeder arrangement held ready until it is again desired to supply a yarn to a knitted fabric.

With these objects in view, an embodiment of the present invention comprises stationary cutting means, preferably mounted on a feeder plate having a guide face, a feeder member having an eye for a yarn, support means for supporting the feeder member for movement between a first normal position in which the eye is located at the level of the dial needles of the knitting machine, a second position in which the eye is located below the dial needles so that a yarn passing through the eye is caught by the dial needles and a third position above the dial needles for holding the yarn against a cutting means and the guide surface of the feeder plate whereby the yarn is cut, and control means for the feeder member, for example electromagnetic means mounted on the support means. At the beginning of an operation, the feeder member has a cutoff yarn end in its eye, and is in its first position. The control means move the feeder member, whenever desired, from the first normal position to the second position so that the yarn in the eye of the feeder member is caught by the dial needles. This movement is short, and the feeder member is immediately moved back to the first position so that the caught yarn is knitted by the dial needles and the cylinder needles. When knitting of the yarn is no longer desired, the control means shift the feeder member to the third position in which the yarn is held against the cutting means, and is cut off. Thereupon, the feeder member is moved back to its normal position holding a cutoff yarn end in readiness for the next supply operation.

In the preferred embodiment of the present invention, a clamping means is provided on the support means for clamping the yarn in the eye of the feeder member when

2

the same is in the third position. In this manner, the yarn is tensioned between the portion knitted into the fabric by the needles, and the clamping means and the eye so that the yarn is easily cut by the cutting means.

5 In the preferred embodiment of the present invention, in which the cutting means is mounted on a feeder plate, a clamping member is mounted on the feeder plate intermediate the cutting means and the feeder member, so that the thread end is clamped under the clamping member after being cut off whereby the yarn is securely held in the eye of the feeder member in the normal first position of the feeder member. During the knitting operation, when the feeder member is also in its normal first position, the knitting needles draw the yarn through the eye, and pull the yarn end out of the clamping member.

10 It is also possible to supply all yarns through movable feeder members, in which event all yarns can be varied in accordance with the pattern and design.

15 The novel features which are considered as characteristic for the invention are set forth in particular in the appended claims. The invention itself, however, both as to its construction and its method of operation, together with additional objects and advantages thereof, will be best understood from the following description 20 of specific embodiments when read in connection with the accompanying drawings, in which:

25 FIG. 1 is a perspective view of a feeder arrangement according to one embodiment of the present invention;

30 FIG. 2 is a front view of the feeder arrangement shown in FIG. 1;

35 FIG. 3 is a side view of the feeder arrangement shown in FIG. 1;

40 FIG. 4 is a sectional view of the feeder arrangement taken on line IV—IV in FIG. 2;

45 FIG. 5 is a perspective view illustrating another embodiment of the feeder arrangement of the present invention;

50 FIG. 5a is a sectional view of the feeder support of the embodiment of FIG. 5;

55 FIG. 6 is a fragmentary axial sectional view of a circular knitting machine provided with the feeder arrangement illustrated in FIG. 5; and

60 FIGS. 7a, 7b, 7c, 7d, 7e, 7f, 7g, 7h and 7i, are fragmentary perspective views illustrating successive operational positions of the feeder member of the present invention during a knitting operation on the circular knitting machine shown in FIG. 6.

65 Referring now to the drawings, and more particularly to FIG. 6, a circular knitting machine has a needle cylinder 53 which rotates about a vertical axis, and is provided with vertical grooves on the outer cylindrical surface thereof. A set of cylinder needles 54 is guided in these grooves, the needles having butts 54a guided in tracks of cam means 55 which are fixed in a cam box 56.

70 55 The dial 58 rotates about the same axis, and has radial slots in which the dial needles 57 are guided. Dial needles 57 have butts 57a sliding in the track of the dial cam means 59 which are mounted on the dial cam plate 50. During rotation of the needle cylinder 53, and of dial 58, the cylinder needles and dial needles will be advanced and retracted in a selected sequence to perform a knitting operation. The dial and knitting needles are of the well known type provided with hooks and latches.

75 Cams 55 and 59 have adjustable cam parts by which selected cylinder needles and dial needles are moved to knit position. Electromagnetic means 60 and 61 are provided for operating the dial cam means 59 for this purpose. The cylinder needles 54 are controlled by conventional pattern wheels.

80 A feeder arrangement according to the present invention is mounted at each feed station which also has a set

of electromagnetic control means 60, 61 for the cams of the dial needles, and a pattern wheel for the cylinder needles. Micro switches are indicated in FIG. 6 at 62, 63 and 64 and are controlled by cams 62a, 63a, 64a which are mounted on the dial 58 for turning movement therewith. Cam followers connect cams 62a, 63a, 64a with the switches 62, 63, 64 so that the same are operated in a selected sequence determined by the cams. Cams 62a, 63a, 64a are provided in the opening through which the adjustment of the dial cams is effected. The micro switches control electromagnetic means 60, 61 and electromagnetic means 15 for the feeder member 2, as will be described hereinafter.

At each feed station of the machine, a holding means 26 is secured to the dial cam cap 50 and supports a feeder arrangement of the present invention, as better seen in FIG. 5. A shaft 25 is turnable in bearings of holding means 26, and a member 34 is attached by a screw 25a to shaft 25. Screw 25a passes through a slot in member 34, so that the position of member 34 can be longitudinally adjusted on shaft 25. A feeder plate 18 is secured by a screw 118 to the lower end of member 34, while the upper end of member 34 turnably supports a support means 33 which can be clamped in adjusted positions by a screw 34a. Support means 33 comprises two springy parts surrounding a tubular member 3, so that the same is clamped in support 33 when screw 33a is tightened. Tubular member 3 is part of the support means of the movable feeder member 2 which has an eye 1 for yarn. A clamping member 22, and a cutting means 21 are mounted on the feeder plate 18. Clamping member 22 is a U-shaped wire secured by screw 23 to a projecting part of the feeder plate which permits an adjustment of clamping member 22. The yoke portion of the U-shaped member clamping member 22 is bent outwardly at 22a.

Feeder plate 18 has a pointed end trailing in direction of the movement of the needles and having a sharp edge in the region of the latches of the cylinder needles. At the thicker leading end, an eye 20 for a yarn may be provided, which extends from the front face of feeder plate 18 to the bottom face 18c. A downwardly inclined face 18z is located adjacent bottom face 18c, and the cutting edge 21a of cutting means 21 is located in this region and extends transverse to a flat guide face 18h. A concave guide face 18d extends from the flat guide face 18h toward the pointed end of feeder plate 18. Clamping member 22 is located on the flat guide face 18h adjacent a shoulder between guide face 18h and the face 18e on the leading end 18b of feeder member 18.

As is best seen in FIG. 6, the rear face of feeder plate 18 is located in a plane tangential to the circle of the cylinder needles 54, and the feeder member 2 is located in a radial plane passing through the axis of rotation of the dial 58 and the cylinder 53, and is inclined at an acute angle to the feeder plate 18. The support arrangement for the feeder member 2 is best seen in FIG. 5a. Tubular member 3, which is clamped in support 33, is closed at its upper end by an end member 80 provided with a bearing bore in which the rod-shaped feeder member 2 is slidably mounted. The other end of tubular member 3 is closed by a conical member 30 in which a sleeve 31 is slidably mounted, sleeve 31 being arrested by a screw 32 in adjusted positions. A projection 14 is provided on the feeder member 2, and engaged by flanged bushings 10 and 11. A pair of springs 12 and 13 abuts end member 80 and sleeve 31, as well as bushings 10 and 11, so that feeder member 2 is held in a normal position in which the eye 1 is substantially located at the level of the bottom face 18c of the feeder plate and on the level of the dial needles 57.

Projecting part 14 is provided with a longitudinal slot 14a in which a pin 104 is located for preventing turning of feeder member 2. Electromagnetic means 15 including two coils are located in tubular member 3 and surround the projecting portion 14, which is made of a mag-

netizable material so that energization of one of the coils of electromagnetic means 15 will shift feeder member 2 upwards, while energization of the other coil will shift feeder member 2 downwards out of its normal position into which it is urged by springs 12 and 13, and held by arresting means 81.

A wire 51 is connected to electromagnetic means 15 and has at the end thereof a plug 52 which is plugged into a corresponding socket on the machine, as best seen in FIG. 6.

The lower end of feeder member 2 is somewhat thicker as shown at 2a so as to be slidably guided in the tubular sleeve 31. The end of feeder member 2 is reduced adjacent the eye 1, and a conical part 2b is attached thereto by screw 2c so that the surface of feeder member 2 flares between eye 1 and the end of the feeder member.

When feeder member 2 is moved to its upper position by energization of the electromagnetic means 15, the eye 1 moves into the bore of the tubular sleeve 31 until the conical part 2b prevents further movement. A yarn passing through eye 1 will be clamped in this position between the end of tubular clamping means 31 and the end portion of feeder member 2.

Referring again to FIG. 5, it will be seen that clamping member 22 is located between feeder member 2 and cutting means 21, although, of course, feeder member 2 is transversely spaced from the plane in which the flat surface 18h, clamping member 22, and cutting means 21 are located. The operation of the feeding arrangement of the present invention illustrated in FIGS. 5, 5a and 6, will be best understood with reference to FIGS. 7a to 7i which illustrate different positions assumed by the feeder member during a knitting operation. Cylinder 53 and dial 58 are only schematically indicated in FIGS. 7a to 7i, and the needles are not shown for the sake of clarity, except where required for an understanding of the operation.

FIG. 7a shows feeder member 2 in a first position into which it is urged by springs 12 and 13. In this normal position, the eye 1 is located substantially at the level of the dial needles. In FIG. 7a, the yarn 28 passes through eye 1, is clamped on flat face 18h by clamping member 22, and has a free end which may slide on cylinder 53, or hang down. It is also possible that this free end is cut off by cutting means 21 due to a preceding operation, as will be explained hereinafter. When it is desired to supply yarn 28 to the needles, the electromagnetic means 15 is energized, for example by micro switch 62 under control of cam 62a, so that feeder member 2 is shifted to a lower second position in which the eye 1 is located below the level of the dial needles, as shown in FIG. 7b.

Since feeder member 2 is stationary, and dial 58 moves with dial needles 57 in direction of the arrow 57c in FIG. 7c, the dial needles 57 pass feeder member 2 and a dial needle 57' will catch thread 28 since the same extends across the plane of the dial needles from the clamping member 22 to the eye 1 of feeder member 2.

As the dial 58 turns further, successive dial needles 57" catch the thread between dial needle 57' and feeder member 2, as shown in FIGS. 7d and 7e. Between the position shown in FIG. 7c and the position shown in FIG. 7e, the respective coil of electromagnetic means 15 have been deenergized, so that feeder member 2 returns to its normal position in which eye 1 is located at the level of the dial needles.

The yarn 28 is thus knitted by needles 54 and 57, and it is possible to knit the fabric only of yarn 28, or to supply another yarn through the eye 20 in the feeder plate 18.

As the dial moves on with the needles 57, yarn 28 is drawn through eye 1, and finally the yarn end, which was held under clamping member 22, is pulled out of clamping member 22 so that the position of FIG. 7f is obtained. The knitting of yarn 28 may now be continued in the normal position of feeder member 2 as shown

in FIG. 7g, while yarn 28 is drawn through eye 1 while being supplied from a suitable yarn reel, not shown.

When it is no longer desired to feed yarn 28 to the fabric, the other coil of the electromagnetic means is energized by operation of a micro switch under control of a cam, and feeder member 2 is raised to its higher position in which the eye 1 is at least partly located in tubular clamping means 31 and is clamped between the same and the conical part 2b. The upward movement of the feeder member 2 pulls the yarn in a position in which it slides along flat face 18h under the clamping member 22, while the yarn portion between feeder member 2 and clamping member 22 is pressed against the face 18d. The yarn is urged into this position since the needles apply tension to the yarn which is clamped at the end of clamping means 31. The thus tensioned yarn is urged against the cutting edge of cutting means 21, as shown in FIG. 7i, drawn across the cutting edge, and frayed by the scraping action of the cutting edge until severed, with the yarn end remaining clamped by clamping member 22. The feeder member 2 is immediately returned to its normal position corresponding to the position of FIG. 7a, so that the yarn end remains clamped under clamping member 22, while being held in readiness for the next knitting operation, which is started as explained above by moving feeder member 2 downward as shown in FIG. 7b.

When the unit 2, 3, 33, 34 and 18 is turned with shaft 25 in holding means 26, feeder member 2 and feeder plate 18 move away from the needles, permitting access to the same for repair purposes, or for the exchange of damaged needles. When the unit is returned to its operative position, the shaft 25 is secured against turning movement by a suitable screw, not shown in FIG. 5. An angular adjustment of the feeder member in a plane perpendicular to the plate can be obtained by loosening screw 34a, turning of support 33 about the same, and again tightening screw 34a. The vertical position of feeder member 2 and feeder plate 18 with respect to the dial needles can be adjusted by loosening screw 25a and by shifting feeder plate 18 which is possible since screw 25a is located in a slot in member 34. Screw 118 permits an adjustment of the feeder plate 18 in tangential direction with respect to the dial needles, whereby the spacing between feeder member 2, and members 21, 22 can be adjusted in this direction.

It will be understood that the electromagnetic means 15 and springs 12 and 13 effect very rapid movements of the feeder member out of its normal position to the lower yarn inserting position, and to the higher cutting off position.

Referring now to the embodiment illustrated in FIGS. 1 to 4, and particularly to FIG. 4, a tubular member 3' houses electromagnetic means 15' and is closed by end plates 8' and 9' in which bearing walls for the rod-shaped feeder member 2' are provided. A projecting core member 14' is located in electromagnetic means 15', and is urged by a pair of springs 12' and 13' acting on bushings 10' and 11' to assume a normal position in which the eye 1' of the feeder member is located at the level of the dial needles. FIG. 4 shows the higher position of the feeder member in which the eye is in the position 1a' in which yarn 28 is clamped against the tubular clamping means 9a'. FIG. 3 shows in solid lines the same position of feeder member 2', and in dash and dot lines the normal position of feeder member 2' in which the eye 1' is located at the level of the dial needles, and substantially at the level of the bottom face 18c' of the feeder plate 18'.

The tubular member 3' is clamped in a support 17'. A bracket 6' is secured by a screw 16' to support 17' which permits adjustment of the height of bracket 6'. A slot 5' in bracket 6' slidably receives pins 4' secured to feeder member 2', so that the feeder member cannot turn. The rear surface of support 17' is provided with an oblique guide face 17a' in which an extension of the feeder

plate is slidably mounted. The selected position of feeder plate 18' can be fixed by a screw 19'. The extension of feeder plate 18' is provided with a slot and passes between two bearing portions of the holding means 26'. A screw 24' passes through the slot, and is threaded into shaft 25', as best seen in FIGS. 1 and 4. Consequently, the extension of plate member 18' passes into the recess 26a between the bearing portions of holding means 26' when shaft 25' is turned. In this manner, the entire unit can be turned into a position in which access to the cylinder and dial needles is possible, as previously explained with reference to FIG. 6. A screw 26b is provided for attaching the entire unit to the dial cam cap.

The main part of the feeder plate has a pointed curved end with a guiding surface 18a', while the other end 18b' is provided with an eye 20' passing from the front face of feeder plate 18' to the bottom face 18c' where it opens in an opening 20a' through which a yarn may be provided from the rear of the feeder plate to the front of the feeder plate and to the needles. Feeder member 2' is arranged opposite the center portion of the feeder plate, and a clamping wire member 22' and a cutting means 21' are mounted on the front face of the feeder member. The bottom face 18c' defines an obtuse angle to the direction of movement of feeder member 2', and extends from the region of the feeder member to the right hand end 18b' of the feeder plate. A surface portion 18d' extends at an acute angle to the direction of movement of feeder member 2', and merges with a curved portion into the bottom face 18c'. The cutting means 21' is located on the surface portion 18d' and has a cutting edge 21a' in the region of the bottom face 18c' and of the curved downwardly inclined surface portion 18z'. The clamping member 22' is adjustably secured to feeder plate 18 by a screw 23', and has a forwardly bent yoke portion 22a' located in the region of the bottom face of the feeder plate. A rounded projection 18f' is located behind the portion 22a', and as best seen in FIG. 3, projects from a flat portion of bottom face 18c'. Projection 18f' is slightly narrower than the U-shaped wire clamping member 22'. The embodiment illustrated in FIGS. 1 to 4 operates in accordance with the same principle as the embodiment described with reference to FIGS. 5 to 7i. A yarn 27 may pass through the stationary eye 20' and be knitted in the conventional manner. However, it is also possible to supply yarn only by the feeder member 2', or to supply several yarns by several feeder members 2' mounted on the respective feed station. The feeder member 2' is in its normal position in which the eye 1' is located at the level of the bottom face of feeder plate 18', as shown in FIG. 2 in solid lines and in FIG. 3 in dash and dot lines. The yarn 28 coming from a yarn supply reel through the eye 1' passes over the curved concave face 18g' and behind the projection 18f' along the bottom face 18c' into the region of the other thread 27, as shown in FIG. 2. This is the normal knitting position of feeder member 2', and corresponds to the position illustrated in FIG. 7g.

When it is no longer desired to supply a yarn 28 to the needles, an impulse is given to the upper coil of the electromagnetic means 15' to energize the same whereby the feeder member 2' is raised to its higher position illustrated in FIGS. 3 and 4 in which the eye is in the position 1a' and the yarn 28 is clamped by the tubular clamping means 9a'.

In this position, yarn 28 extends from eye 1 in position 1a to the bottom face 18c' as indicated by a dotted line in FIG. 2 and in FIG. 4. Since yarn 28 is knitted by the needles which move away from feeder member 2' and feeder plate 18', a pull is exerted on the clamped yarn 28 so that the same slips over projection 18f' onto face portion 18h' of feeder plate 18' and under clamping member 22'. The bent end portion 22a' guides the yarn toward the edge 21a' of cutting means 21'. The pull exerted by the knitting needles on yarn 28 urges the same against the edge 21a' so that the yarn is cut off. During

this operation, electromagnetic means 15' is deenergized, and the springs return feeder member 2' to its normal position with the cut off yarn end clamped under clamping member 22' as shown in broken lines in FIG. 2. The device is now in a position of readiness.

It is again desired to knit yarn 28 into the fabric, the other coil of the electromagnetic means 15' is energized so that feeder member 21 is moved to its lower position in which eye 1' is in the position 1b', as indicated in broken lines in FIG. 2. The yarn portion between clamping member 22' and the lowered eye 1b' extends across the dial needles, substantially as explained with reference to FIGS. 7b and 7c, so that yarn 28 is caught by the needles which knit yarn 28 while spring 13' returns feeder member 2' to its normal position in which yarn 28 is guided by the bottom face 18c' behind projection 18f', as shown in FIG. 2. During the knitting operation, the yarn is drawn through eye 1', and the clamped yarn end is pulled out of the clamping member 22' as described with reference to FIG. 7f.

In the illustrated embodiments, the electromagnetic means 15' constitutes operating means for the feeder member, and is controlled by remote control means including cams on the dial 58, and micro switches controlled by cam followers cooperating with the control cams, as shown in FIG. 6. Instead of electromagnetic means, hydraulic operating means may be provided including a piston in tubular member 3. The piston is shifted by fluid supplied under control of control valves which may be operated by cams corresponding to the arrangement of the micro switches 62 to 64 and the cams 62a to 64a. The operating means may also be controlled by electro-hydraulic program control means in a manner explained in the textbook "Hydraulische Antriebe," A. Duerr and O. Wachter, page 185. A mechanically controlled control valve for the hydraulic operating means is described in the same textbook on page 117.

It will be understood that each of the elements described above, or two or more together, may also find a useful application in other types of circular knitting machines differing from the types described above.

While the invention has been illustrated and described as embodied in a feeder arrangement for circular knitting machines having dial needles and cylinder needles, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a circular knitting machine, in combination, a set of cylinder needles; a set of dial needles; cutting means; a feeder member having a part for guiding a yarn; support means for supporting said feeder member for movement between a first normal position in which said part is located in the region of said dial needles, a second position in which said part is located relative to said dial needles so that a yarn guided by said part is caught by said dial needles, and a third position for holding the yarn at said cutting means so that the yarn is cut; and control means for moving said feeder member holding a cutoff yarn from said first normal position to said second position so that the yarn is caught by said dial needles, back to said first position so that the yarn is knitted, to said third position so that the yarn is cut, and back to said first position for holding the cut yarn end.

2. In a circular knitting machine, in combination, a set of cylinder needles; a set of dial needles; a feeder plate located in the working region of said cylinder and dial needles and having a guide surface; cutting means mounted on said feeder plate; a feeder member having an eye for a yarn and being located opposite said guide surface; support means for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut, and back to said first position for holding the cut yarn end.

3. In a circular knitting machine, in combination, a set of cylinder needles; a set of dial needles; a feeder plate located in the working region of said cylinder and dial needles and having a guide surface; cutting means mounted on said feeder plate; a feeder member having an eye for a yarn and being located opposite said guide surface; support means for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn on said guide surface of said feeder plate and against said cutting means whereby the yarn is cut, said support means including a clamping means cooperating with said feeder member in said third position for clamping the yarn in the eye of said feeder member so that the yarn is tensioned on said guide surface of said feeder plate between said cutting means and clamping means during the cut; and control means for moving said feeder member holding a cutoff yarn from said first normal position to said second position so that the yarn is caught by said dial needles, back to said first position so that the yarn is knitted, to said third position so that the yarn is cut, and back to said first position for holding the cut yarn end.

4. In a circular knitting machine, in combination, a set of cylinder needles; a set of dial needles; a feeder plate located in the working region of said cylinder and dial needles and having a guide surface; cutting means mounted on said feeder plate; a feeder member having an eye for a yarn and being located opposite said guide surface; a clamping member mounted on said feeder plate intermediate said cutting means and said feeder member; support means for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

5. In a circular knitting machine, in combination, a set of cylinder needles; a set of dial needles; a feeder plate located in the working region of said cylinder and

dial needles and having a guide surface; cutting means mounted on said feeder plate; a feeder member having an eye for a yarn and being located opposite said guide surface; a clamping member mounted on said feeder plate intermediate said cutting means and said feeder member; support means for supporting said feeder member for movement between a first normal position in which said eye is located substantially at the level of said dial needles, a second position in which said eye is located below the level of said dial needles, and a third position above the level of said dial needles for holding the yarn under said clamping member on said guide surface of said feeder plate and against said cutting means whereby the yarn is cut, said support means including a clamping means cooperating with said feeder member in said third position for clamping the yarn in the eye of said feeder member so that the yarn is tensioned on said guide surface of said feeder plate under said clamping member between said cutting means and clamping means during the cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

6. In a circular knitting machine, in combination, a set of cylinder needles; a set of dial needles; a feeder plate located in the working region of said cylinder and dial needles and having a guide surface and an eye for supplying a yarn to said cylinder and dial needles; cutting means mounted on said feeder plate; a feeder member having an eye for a yarn and being located opposite said guide surface; a clamping member mounted on said feeder plate intermediate said cutting means and said feeder member; support means for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

7. In a circular knitting machine, in combination, a set of cylinder needles; a set of dial needles; a feeder plate located in the working region of said cylinder and dial needles and having a guide surface and a bottom face formed with a projection adjacent said guide surface; cutting means mounted on said feeder plate; a feeder member having an eye for a yarn and being located opposite said guide surface; a clamping member mounted on said feeder plate intermediate said cutting means and said feeder member and above said projection on said bottom face of said feeder plate; support means for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving said feeder member holding a cutoff yarn from said first normal position to said second position so

that the yarn is caught by said dial needles, back to said first position so that the yarn is guided on said bottom face behind said projection while being knitted, to said third position so that the yarn slips over said projection onto said guide face under said clamping member and is cut and has the end thereof clamped by said clamping member on said feeder plate, and back to said first position for holding the cut and clamped yarn end.

8. In a circular knitting machine, in combination, a set of cylinder needles; a set of dial needles; a feeder plate located in the working region of said cylinder and dial needles and having a guide surface and a bottom face formed with a projection adjacent said guide surface; cutting means mounted on said feeder plate; a feeder member having an eye for a yarn and being located opposite said guide surface; a clamping member mounted on said feeder plate intermediate said cutting means and said feeder member and above said projection on said bottom face of said feeder plate; support means for supporting said feeder member for movement between a first normal position in which said eye is located substantially at the level of said dial needles and at the level of said bottom face of said feeder plate, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut, said support means including a clamping means cooperating with said feeder member in said third position for clamping the yarn in the eye of said feeder member so that the yarn is tensioned on said guide surface of said feeder plate between said cutting means and clamping means during the cut; and control means for moving said feeder member holding a cutoff yarn from said first normal position to said second position so that the yarn is caught by said dial needles, back to said first position so that the yarn is guided on said bottom face behind said projection while being knitted, to said third position so that the yarn slips over said projection onto said guide face under said clamping member and is cut and has the end thereof clamped by said clamping member on said feeder plate, and back to said first position for holding the cut and clamped yarn end.

9. In a circular knitting machine, in combination, a set of cylinder needles; a set of dial needles; a feeder plate located in the working region of said cylinder and dial needles and having a guide surface; cutting means mounted on said feeder plate; a feeder member having an eye for a yarn and being located opposite said guide surface; a clamping member mounted on said feeder plate intermediate said cutting means and said feeder member; support means mounted on said feeder plate for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

10. An arrangement as set forth in claim 9 wherein said feeder plate has an upright extension projecting upwardly from the same; and wherein said support means is movably mounted on said extension for adjusting move-

ment toward and away from, and parallel to said guide surface; and means for securing said support means on said extension in adjusted positions whereby the position of said eye of said feeder member in said first normal position is determined.

11. In a circular knitting machine, in combination, a set of cylinder needles; a set of dial needles; a dial cam cap; a feeder plate located in the working region of said cylinder and dial needles and having a guide surface; cutting means mounted on said feeder plate; a feeder member having an eye for a yarn and being located opposite said guide surface; a clamping member mounted on said feeder plate intermediate said cutting means and said feeder member; support means mounted on said feeder plate for supporting said feeder member for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; holder means for supporting said feeder plate with said support means and feeder member on said dial cam plate movable between a normal operative position, and a position retracted from the working region of said cylinder and dial needles; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

12. An arrangement as set forth in claim 11 wherein said holder means includes a bearing means secured to said dial cam cap, a horizontal shaft turnably mounted in said bearing means, and means for securing said feeder plate to said shaft for turning movement with the same between said normal and retracted positions.

13. In a circular knitting machine, in combination, a set of cylinder needles; a set of dial needles; a feeder plate located in the working region of said cylinder and dial needles and having a guide surface; cutting means mounted on said feeder plate; a plurality of feeder members, each feeder member having an eye for a yarn and being located opposite said guide surface; a clamping member mounted on said feeder plate intermediate said cutting means and said feeder member; support means for supporting each of said feeder members for movement between a first normal position in which said eye is located substantially at the level of said dial needles, said eyes of said feeder members being located at the same point when said feeder members are in said first position, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving selected feeder members holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

14. An arrangement as set forth in claim 4 wherein said feeder plate has a pointed end trailing in direction of the movement of said needles and a sharp edge in the region of said pointed end, wherein said guide sur-

face is concave in the region of said pointed end, has a flat portion in the region of said clamping member, and has a downwardly inclined surface portion in the region of its other end, said cutting means being a cutting blade located in the region of said downwardly inclined surface portion and having a cutting edge closely spaced from said clamping member and extending transversely through the plane of said flat portion of said guide surface so that a yarn held by said clamping member on said flat portion is guided onto said cutting edge.

15. An arrangement as set forth in claim 14 wherein said clamping member is a substantially U-shaped wire member having leg portions resiliently abutting said flat portion of said guide surface, and an outwardly bent yoke portion located at the level of the bottom surface of said feeder plate.

16. An arrangement as set forth in claim 15 wherein said feeder plate has between said other end thereof and said flat portion of said guide surface, a shoulder, one leg of said wire member being located adjacent said shoulder.

17. An arrangement as set forth in claim 15 and including means for adjustably mounting said wire member on said feeder plate.

18. An arrangement as set forth in claim 14 wherein said feeder plate has a flat substantially horizontal bottom face at said other end thereof merging into said downwardly inclined surface, and a projection on said bottom face adjacent said flat portion of said guide surface located in the region of said clamping member so that a yarn may be guided on said bottom face behind said projection and over said downwardly inclined surface, said cutting edge being located above said projection and said bottom face.

19. In a circular knitting machine, in combination, a set of cylinder needles; a set of dial needles; a feeder plate located in the working region of said cylinder and dial needles and having a substantially vertical guide surface; cutting means mounted on said feeder plate; a feeder member of elongated shape having at one end thereof an eye for a yarn and being located opposite said guide surface; a clamping member mounted on said feeder plate intermediate said cutting means and said feeder member; support means for supporting said feeder member in a position inclined to said guide face and located in a radial plane with respect to said dial needles, and for movement between a first normal position in which said eye is located substantially at the level of said dial needles, a second position in which said eye is located below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

20. In a circular knitting machine, in combination, a set of cylinder needles; a set of dial needles; a feeder plate located in the working region of said cylinder and dial needles and having a guide surface; cutting means mounted on said feeder plate; a feeder member having an eye for a yarn and being located opposite said guide surface; a clamping member mounted on said feeder plate intermediate said cutting means and said feeder member; support means for supporting said feeder member for movement between a first normal position in which said eye is located substantially at the level of said dial needles, a second position in which said eye is located

below the level of said dial needles so that a yarn passing through said eye is caught by said dial needles, and a third position above the level of said dial needles for holding the yarn under said clamping member on said guide surface of said feeder plate and against said cutting means whereby the yarn is cut; and control means including remote controlled operating means mounted on said support means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.

21. An arrangement as set forth in claim 20 wherein said support means includes a tubular member, a pair of end members at the ends of said tubular member having aligned bearing bores; and wherein said feeder member has a rod-shaped portion passing through said bearing bores; and wherein said operating means is located in said tubular member.

22. An arrangement as set forth in claim 21 and including a projecting portion on said rod-shaped portion; and springs abutting said projecting portion and said end members, respectively, for holding said rod-shaped portion in a position in which said feeder member is in said first normal position so that said feeder member tends to return to said first normal position.

23. An arrangement as set forth in claim 20 wherein said operating means is an electromagnetic means located in said tubular member; and wherein said feeder member has a core portion located in said tubular member in the region of said electromagnetic means so that the feeder member is shifted when said electromagnetic means is energized.

24. An arrangement as set forth in claim 20 wherein said support means include a tubular member, and a pair of end members formed with bearing bores; wherein said operating means is a pair of electromagnetic coils; wherein said feeder member has a rod-shaped portion slidably guided in said bearing bores for longitudinal movement, and an electromagnetic core member on said rod-shaped portion located within said electromagnetic coils so as to be shifted by the same in opposite directions for moving said feeder member to said second and third positions, respectively; and a pair of springs abutting said core member and said end members, respectively, for holding said feeder member in said first normal position.

25. An arrangement as set forth in claim 24 and including a tubular clamping means mounted on said support means surrounding and slidably guiding said rod-shaped portion of said feeder member in the region of said eye; and wherein said eye is at least partly located in said tubular clamping means in said third position of said feeder member whereby a yarn passing through said

eye is clamped between said tubular clamping means and said feeder member.

26. An arrangement as set forth in claim 20 and including a tubular clamping means mounted on said support means surrounding and slidably guiding said feeder member in the region of said eye; and wherein said eye is at least partly located in said tubular clamping means in said third position of said feeder member whereby a yarn passing through said eye is clamped between said tubular clamping means and said feeder member.

27. An arrangement as set forth in claim 26 wherein said feeder member has said eye spaced a short distance from one end thereof, said feeder member having a flaring surface between said eye and said one end for clamping the yarn against said tubular clamping means.

28. An arrangement as set forth in claim 27 wherein said feeder member has a rod-shaped part, and a conical part secured to said one end adjacent said eye and providing said flaring surface.

29. An arrangement as set forth in claim 26 and including means for adjusting the position of said tubular clamping means on said support means and along said feeder member.

30. In a circular knitting machine, in combination, a set of cylinder needles; a set of dial needles; means for rotating said sets of needles about an axis of rotation; a feeder plate located in the working region of said cylinder and dial needles and having a guide surface; cutting means mounted on said feeder plate; a feeder member having an eye for a yarn and being located opposite said guide surface; a clamping member mounted on said feeder plate intermediate said cutting means and said feeder member; support means for supporting said feeder member for movement in a radial plane through said axis of rotation and in a direction inclined at an acute angle to said axis of rotation between a first normal position in which said eye is located substantially at the level of said dial needles, a second position in which said eye is located below the level of said dial needles and closer spaced in radial direction from said cylinder needles than in said first position so that a yarn passing through said eye is caught by said dial needles, and a third position above the level of said dial needles in which said eye is farther spaced in radial direction from said cylinder needles than in said first position for holding the yarn under said clamping member on said guide surface of said feeder plate and against said cutting means whereby the yarn is cut; and control means for moving said feeder member holding a cutoff yarn from said first normal position to said second position so that the yarn is caught by said dial needles, back to said first position so that the yarn is knitted, to said third position so that the yarn is cut and has the end thereof clamped by said clamping member on said feeder plate, and back to said first position for holding the cut and clamped yarn end.
